UNITED STATES PATENT OFFICE

ALMER H. BRODBECK, OF ST. LOUIS, MISSOURI, ASSIGNOR TO AMERICAN STOVE COMPANY, OF ST. LOUIS, MISSOURI, A CORPORATION OF NEW JERSEY

GAS RANGE

Application filed December 6, 1927. Serial No. 238,058.

This invention relates to improvements in gas ranges, the particular type of range in which the invention is embodied being what is commonly known and referred to as a closed top range.

Closed top ranges have certain advantages over ranges of the open top type, and for this reason there is a demand for this type of range. In a closed top type of range which gets its name from the fact that the top of the range above the burners is solid, it is necessary to make some special provision for the proper movement of secondary air to the burners and of the products of combustion away from the burners so as to ensure that a complete and perfect combustion is had, and that no carbon monoxide is formed.

I have discovered that unless products of combustion are readily and properly taken away or carried off, that a floating of the burners will result, and particularly will this be the case in respect to the rear burners where the range is two burners deep as is the most common way of making ranges for domestic use.

It is therefore necessary to provide a flue space or the equivalent through which to conduct the products of combustion from the front burners past the rear burners, and at the same time provide means whereby secondary air will flow freely and rapidly to the rear burners.

Experimentation having taught me the above facts and principles in respect to closed top gas ranges, I have devised and constructed a gas range of the closed top type which is highly efficient in operation, and which is specifically described in the following specification and claims.

Bearing the above facts in mind, the invention has for its objects the following:

The primary object of the invention is the provision of a gas range of the closed or solid top type having means for ensuring the proper movement of secondary air to the burners and the proper conducting of the products of combustion away from the operating burners so that complete and perfect combustion is had, and there is no formation of carbon monoxide.

Another object of the invention is the provision of a closed or solid top gas range in which the floating of the burners during operation is avoided.

A still further object of the invention is the provision in a gas range of the type described, of means for carrying the products of combustion from the front burners past the rear burners and keeping these products of combustion above the rear burners so that secondary air can readily flow to all the burners and be delivered to them from their under sides.

A further object of the invention is the provision of a stove of the type described which is highly efficient in operation.

Other further objects, novel features of construction and improved results will appear from the following description and accompanying drawings.

In the drawings:

Figure 1 is a top plan view of the cooking top of a gas range of the closed top type, the rear ends of the cooking top being broken away and shown in horizontal section.

Figure 2 is a vertical sectional view taken on the line 2—2 of Figure 1, looking in the direction indicated by arrows.

Figure 3 is a transverse vertical sectional view taken on the line 3—3 of Figure 1, looking in the direction indicated by arrows.

Figure 4 is a rear view of an entire range embodying my invention.

Figure 5 is a top plan view of a gas range of the closed top type showing a modified form of my invention, the rear end of the cooking top being broken away and shown in horizontal section.

Figure 6 is a longitudinal vertical sectional view taken on the line 6—6 of Figure 5, looking in the direction indicated by arrows.

Figure 7 is a transverse vertical sectional view, taken on the line 7—7 of Figure 5, looking in the direction indicated by arrows.

Figure 8 is a rear view of a gas range having thereto applied the modified form of my invention.

Describing the invention in detail, reference being had to the accompanying drawings, it will be seen that the range proper is designated by A, while B indicates the oven

side of the range, C the cooking top side of the range having below the cooking top the warming oven D.

Referring particularly to Figures 1 to 4 inclusive, 10 indicates the top frame which supports the solid cooking top 11 which top is provided with a plurality of removable covers or lids 12 positioned above the front and rear top or cooking burners.

10 The gas supply conduit is indicated at 13 and is supported in front of and below the cooking top by suitable brackets 14. The range front below the cooking top is open as indicated at 15, and a drip pan 16, supported on a suitable slideway 17, forms the bottom of the burner chamber E, the top of which is formed by the solid cooking top 11.

15 The front burners are indicated at 18 and the rear burners at 19; these burners being positioned in the chamber E, and provided with the usual mixing tubes 20, the outer ends of which extend through the open front portion 15 and are connected to the gas supply pipe 13 through the medium of gas valves 21.

20 25 The form of burners illustrated in the drawings is that wherein the front or outer ends of the mixing tubes are supported through their connection with the gas valves which in turn are supported by the main supply pipe, while the rear end of the rear burner is supported by a suitable bracket 22. Intermediate the length of the rear burner mixing tube, the tube is provided with an outwardly extending bracket 23 which supports the rear end of the front burner 18.

30 35 The primary air for both front and rear burners is taken in, as is common practice, through the usual shuttered, bell-shaped ends 24 of the mixing tubes. The secondary air enters the open front portion 15 of the range and is delivered to the burners from their under sides.

40 45 The range is provided with an outlet flue or stack 25 for carrying off the products of combustion of all or any of the burner chambers in operation. As clearly appears in Figure 2 of the drawings, the bottom 26 of this outlet flue has an end 27 extending into the burner chamber E.

50 55 The sub-member or baffle which comprises the essence of this invention, is designated by the letter F, and is positioned above the rear burners of the range and below the closed top 11. This sub-member has a vertical front wall 28, side walls 29 which extend rearwardly to the rear end of the burner chamber. The sub-member has a bottom 30 in which are provided openings 31 of a size or diameter slightly greater than the size or diameter of the rear burners 19 so as to provide a space for the admission or passage upwardly of the secondary air from beneath the burner.

60 65 The sub-member is supported in position by reason of the fact that the rear end of

the bottom 30 rests upon and is fastened to the inwardly extending end 27 of the outlet flue bottom 26.

In Figure 2 of the drawings, the travel of secondary air and the products of combustion is indicated by arrows. The plain arrows indicate the travel of the secondary air while the feathered arrows indicate the travel of the products of combustion.

In this form of the invention, it will be seen that the rear burner mixing tubes are below the sub-member, the burners themselves extending upwardly into the sub-member through the openings 31 provided for that purpose. The secondary air entering the open front 15 travels under the front burners and under the sub-member, reaching the rear burners from their bottom sides through the opening 31. The products of combustion from the front burners are directed and kept above the rear burners through the medium of the sub-member, and these products of combustion travel from the rear burners out of the open rear end through the said sub-member into and up the outlet flue 25.

The function of the sub-member is to provide a flue to insure that the products of combustion from the front burners pass above the rear burners so as not to in any way interfere with the flow of secondary air to the underside of the rear burners. It has been found that in a closed top range, this control and direction of the products of combustion from the front burners is absolutely essential or otherwise these products of combustion of the front burners have a tendency to smother the rear burners.

In Figures 5 to 7, inclusive, an alternate form of the invention is illustrated. The purpose and operation of this alternate form is practically identical with that described above, although the alternate form differs in slightly different details of construction.

By reference to Figures 6 and 7, it will be seen that the sub-member of baffle is designated by the letter G, and that here also the sub-member has side walls 51, bottom 52, and open rear end 53, in combination with an outlet flue 54. In this form of the invention the bottom 55 of the outlet flue is shown formed as a continuation of the bottom 52 of the sub-member. The sub-member in this form is supported at its rear end through engagement between its bottom 52 with the rear wall 56 of the range.

The sub-member G is much deeper than the sub-member F, its depth being sufficient to completely enclose the rear burners 19, and also that portion of the mixing tubes immediately adjacent the burners.

The bottom 52 of the sub-member is provided with an opening 59 slightly greater in diameter than the diameter of the burners 19, and an upwardly extending collar 60 is

provided at the edges of this opening. The open end of this collar extends to a point even with the top of the rear burners 19. The purpose of this collar is to direct secondary air for use.

5 In Figure 6 of the drawing, the direction of movement of the secondary air is illustrated by plain arrows, and the direction of movement of the products of combustion by feathered arrows.

10 In this form of the invention the rear wall 56 of the range is shown provided with a plurality of openings 61 for the admission of secondary air for use with the rear burners.

15 Although this form is illustrated, I desire it to be understood that these rear openings 61 are not essential to the principle of operation of the rear burners. In some instances they are desirable as at certain times and under 20 certain conditions the front burners generate a heat sufficient to prevent the admission of sufficient secondary air through the open front 15 to take care of the necessary supply of secondary air to the rear burners.

25 From the foregoing it will be seen that in both forms of the invention there is provided a sub-member or baffle positioned and constructed to direct the products of combustion of the front burners above the rear burners 20 during their passage rearwardly to the outlet flue and that provision is made in the sub-members for the admission of secondary air to the rear burners.

30 It is thought that it will be further readily understood that this control of the products of combustion is necessary and essential in the closed top type of range to secure satisfactory and perfect combustion so that no carbon monoxide is formed and to prevent 35 the smothering and floating of the rear burners during their operation.

Having thus described my invention, what I desire to claim and secure by Letters Patent is:

45 1. A gas range having a closed cooking top with a burner chamber there below, said chamber having an open front end and its rear end in communication with an outlet flue, front and rear burners in said chamber, 50 a sub-member in said chamber, said sub-member surrounding said rear burner and forming a secondary burner chamber above the burner, said secondary burner chamber in communication with the main burner chamber at its top and bottom, and the rear end 55 of said secondary burner chamber in communication with said outlet flue, the products of combustion from the front burners entering said secondary chamber from its top and the secondary air for the rear burners entering said supplemental burner chamber from its bottom.

60 2. A gas range having a solid top, a burner chamber below said top having an open front end for the admission of secondary air and

having communication at its rear end with an outlet flue for the outlet of the products of combustion, front and rear burners in said burner chamber, a sub-member of a width substantially the width of the burner chamber 70 and positioned above and surrounding said rear burners, said sub-member forming a secondary burner chamber having an open top, open front and an open rear end in communication with said outlet flue, the bottom 75 of said sub-member having openings for the reception of said rear burners, and said openings further acting as means for the admission of secondary air to the rear burners during 80 their operation.

3. A gas range having a solid cooking top, a burner chamber below said top having front and rear burners supported therein, said chamber having an opening at its front end for the admission of secondary air for said 85 burners and at its rear end an outlet flue, a sub-member positioned above said rear burner and extending to a point in front thereof, said sub-member of a width substantially the width of the burner chamber and 90 having a closed bottom and side walls, said bottom and side walls extending to and supported by the bottom of said outlet flue, said construction forming a secondary burner chamber the rear end of which is in communication with said outlet flue, said sub-member having an open top to permit and direct the 95 passage of the products of combustion from the front burner above and past the rear burner to said outlet flue, and an opening in 100 the bottom of said sub-member for the reception of said rear burner and the admission of secondary air thereto.

4. A gas range having a solid cooking top, a burner chamber below said top having front 105 and rear burners supported therein, an opening at the front end of said chamber for the admission of secondary air for said burners, an outlet flue for the products of combustion, a sub-member forming a housing having an 110 open top and a rear end in communication with said outlet flue, the bottom of said sub-member in substantially the same horizontal plane as the top of said rear burner and provided with an opening above the same, said 115 opening of a size to permit the passage of secondary air to said rear burner during its operation and said sub-member directing the passage of the products of combustion from the front burners above and past the rear 120 burners to said outlet flue.

5. A gas range having a closed cooking top with a main burner chamber therebelow, a drip pan forming the bottom of said main burner chamber, a sub-member in the rear 125 end of said burner chamber forming a supplemental burner chamber, a burner in the main burner chamber and a burner having its top in communication with the supplemental burner chamber, means for the admis- 130

sion of secondary air to the main and supplemental burner chambers, and the burner of the supplemental burner chamber positioned within the secondary air inlet of said chamber, communication between the secondary burner chamber and the main burner chamber at the top of said secondary burner chamber for the admission of products of combustion from the main burner chamber, and an outlet flue for the products of combustion in communication with the secondary burner chamber, for the purpose described.

6. A gas range having a closed cooking top with a burner chamber therebelow, a sub-member in the rear end of said burner chamber and extending entirely transverse the same, said sub-member forming a sub-chamber having an open top in communication with the main burner chamber, a burner in the main burner chamber in front of said submember, a burner in the sub-chamber formed by said sub-member, and an outlet flue in communication with said sub-chamber, whereby the products of combustion from the front burner enter the open upper end of the sub-chamber and pass above the burner therein and escape through said outlet flue.

7. A gas range having a closed cooking top with a burner chamber therebelow, a sub-member in the rear end of said burner chamber and extending entirely transverse the same, said sub-member having a vertical front wall thereby forming in the rear end of the main burner chamber a secondary burner chamber, the front wall of said secondary burner chamber stopping short of the cooking top thereby affording communication with the main burner chamber through the open top of said secondary burner chamber, front burners for said range in said main burner chamber and in front of the vertical wall of said sub-chamber, a burner extending into the secondary burner chamber formed by said submember, and an outlet flue in communication with said secondary burner member, whereby the products of combustion from the front burners enter the open upper end of the secondary burner chamber and pass above the burner therein and escape through said outlet flue.

In testimony whereof I hereunto affix my signature.

ALMER H. BRODBECK.
